UNITED STATES PATENT OFFICE

2,457,916

IGNITION APPARATUS

Thabous A. Newton, Flomaton, Ala.

Application January 8, 1946, Serial No. 639,713

1 Claim. (Cl. 123—148)

1

The present invention relates to new and useful improvements in ignition apparatus for internal combustion engines and more particularly to a combined coil and distributor for the spark plugs of the engine.

An important object of the present invention is to provide means for mounting the coil of the ignition system of the engine in the cap of the distributor whereby to arrange the coil and distributor in close operative relation and compactly mounted in a single housing.

A further object of invention is to provide a more efficient arrangement for the circuit wires leading from the distributor to the spark plugs of the engine.

Another object of invention is to provide a locking switch for the ignition system also mounted in the cap of the distributor and independent of the usual ignition switch controlled on the instrument panel of a motor driven vehicle.

A further object of invention is to provide a device of this character of simple and practical construction, which is efficient and reliable in operation, neat and attractive in appearance and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a bottom plan view of the distributor cap.

Figure 3 is an enlarged vertical sectional view of the combined coil and distributor.

Figure 4 is a fragmentary sectional view taken on a line 4—4 of Figure 2.

Figure 5 is a transverse sectional view taken on a line 5—5 of Figure 1, and

Figure 6 is an enlarged fragmentary sectional view showing the terminal between the distributor contact and the spark plug wire embedded in the distributor cap.

Referring now to the drawings in detail wherein for the purpose of illustration I have disclosed a preferred embodiment of invention, the numeral 5 designates the combined coil and distributor housing generally and which includes a cup-like base 6 through the bottom of which the shaft 7 projects for attaching the rotor 8 thereto in the usual manner, the rotor being of conventional construction and including the resilient

2

contact finger 9 secured to the upper portion thereof.

Mounted on the base 6 is a cap 10 detachably secured in position thereon by a conventional form of snap spring catches 11.

The cap 10 is provided with a lower partition 12 from which the center contact 13 projects for engagement with the finger 9 of the rotor and from which a plurality of contacts 14 also project and positioned in circular arrangement in the cap for successive engagement by the spring contact 9 of the outer end of the rotor in the usual manner.

From the contacts 14 circuit wires 15 extend to 15 inverted sockets 16 opening through the bottom of a shoulder 17 extending circumferentially around the side of the cap 10, the sockets being adapted for receiving the ends of circuit wires 18 leading to the spark plugs of an internal combustion engine.

Above the shoulder 17 the cap 10 is of a dome-shaped construction and is formed in its upper portion with a horizontal partition 19 to provide a chamber 20 in the cap and in which a coil 21 of conventional construction is positioned, the coil including the primary winding 22 and secondary winding 23.

The secondary winding 23 is connected to the center contact 13 by a circuit wire 24.

30 A chamber 25 is formed in the top of the cap above the chamber 20 and in the top of which is secured the barrel 26 of a key controlled lock for receiving a key 27 in the top thereof. The lock includes a screw threaded for vertical adjustment in the barrel and to the bottom of the screw and insulated therefrom is a transverse conductor 28 of resilient material adapted upon rotation by the key 27 for vertical movement of its ends into and out of engagement with contact 35 buttons 29 carried by the partition 19 in the chamber 25. One of the contact buttons 29 is connected to the primary winding 22 of the coil while the other contact button has a circuit wire 30 attached thereto and extending outwardly 40 through the sides of the cap 10 for connecting an ignition wire 31 thereto by means of a conventional form of connector 32, the ignition wire 31 being controlled by the usual ignition switch on the instrument panel of the vehicle. The key is 45 enclosed on top of the chamber 25 by a cap 25a.

From the lower end of the primary winding 22 of the coil extends a circuit wire 33 and connected to a terminal 34 projecting through the wall of the base 6 of the distributor housing by 55 means of a connector 35 embedded in the cap

18 and which includes a spring projected plunger 36 slidably mounted in the lower edge of the cap 10. The plunger 36 is adapted to engage the inner end of the terminal 34 to complete the circuit therewith and the terminal 34 provides a connection for the timing mechanism (not shown) of conventional construction also mounted in the base of the distributor.

The form of invention illustrated in Figure 6 of the drawings, the distributor cap 10a has the circuit wires 15a embedded therein leading from the contacts 14a to the sockets 16a for the spark plug wires 18a.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

What I claim is:

In apparatus of the class described, a housing adapted to cap a distributor having a rotor, said housing comprising a pair of upper and lower separate chambers therein, the lower chamber

adapted to contain a coil for connection to the distributor, contacts depending from the bottom of the lower chamber and adapted to be engaged by said rotor, an ignition wire leading into the lower chamber, a pair of contacts in the bottom of the upper chamber adapted to be connected to said wire and coil, a lock barrel suspended in the upper chamber having a member threaded therethrough for rotary adjustment toward and from the bottom of said upper chamber, a conductor carried by said member for bridging said contacts when said member is adjusted toward the bottom of said upper chamber, and a key for rotating said member, said housing having a closure removable for access to said member to insert said key therein.

THABOUS A. NEWTON.
